Attorneys.

UNITED STATES PATENT OFFICE.

GEORGE B. CLARK, OF PITTSBURGH, PENNSYLVANIA.

GAUGE COCK.

Application filed September 15, 1924. Serial No. 737,835.

To all whom it may concern:

Be it known that I, GEORGE B. CLARK, a citizen of the United States, and resident of Pittsburgh, in the county of Allegheny and 5 State of Pennsylvania, have invented a new and useful Improvement in Gauge Cocks; and I do hereby declare the following to be a full, clear, and exact description thereof.

My invention relates to gauge cocks, and 10 particularly to cocks or valves for employment with containers of fluids under pressure, as steam boilers and the like.

My invention is particularly applicable to locomotive boilers although it will be understood that it may be also employed in connection with any container for fluids under pressure, where an auxiliary closing device or valve is desired in connection with a main valve. Gauge cocks such as employed on locomotive boilers must be free from leakage. Leakage permits the escape of steam from the boiler and may tend to obscure the engineer's vision. An engine equipped with a leaky gauge cock may not be employed in interstate commerce, and it frequently happens that a locomotive must be withdrawn from service in order to permit correction of such defect. In the devices heretofore employed, it has been necessary to blow off the boiler to reduce the pressure therein before removing the gauge cock to permit regrinding of the valve or substitution of a new valve.

One object of my invention is to provide 35 a valve which may be quickly and readily regrinded without removing the engine from service and without withdrawing the fire therefrom.

Another object of my invention is to 40 simplify and improve generally the structure and operation of fluid pressure valves.

One form which my invention may take is shown in the accompanying drawing wherein Fig. 1 is a view, partially in side elevation and partially in section, of a gauge cock structure embodying my invention, with the valves thereof in one position; Fig. 2 is a similar view showing the valves in another position; Fig. 3 is a rear elevational view of the auxiliary valve of Figs. 1 and 2; Fig. 4 is a front elevational view thereof; Fig. 5 is a side elevational view of the main valve, and Fig. 6 is a view thereof in front elevation.

For the purpose of illustration, I have

shown my invention applied to a locomotive boiler, only the front sheet 7 of which is illustrated. The sheet 7 is formed in the usual manner, to provide screw thread connection with a valve. In the present instance I provide an auxiliary valve block 8 that has a threaded extension 9 for effecting engagement with the sheet 7. The valve block 8 is provided with a recess within which an auxiliary or check valve 10 may have longitudinal movement. The body portion of the valve 10 is provided with a number of longitudinal recesses 11 (shown more clearly in Figs. 3 and 4) that permit passage of fluid from the forward central aperture 12 of the valve block 8 to the rear end of the valve 10. The rear end of the valve 10 is provided with a seating surface 13 that seats against the forward end of a main valve block 14, to seal the aperture 15 contained in said block 14 against communication with the passage 12 and the interior of the boiler. The valve 10 seats against a rearwardly extending stem 16 as shown in the drawing, but may be formed integrally therewith, and loosely fits within a recess in the main valve 17. In Fig. 1 the rear end of the stem 16 is shown as seated against the bottom of the recess in the valve 17, the valve 10 thus being held in forward position against the pressure in the boiler.

The valve 17 is provided with a rearwardly extending projection 18 that fits loosely within a valve stem 19 that is hollowed at its forward end. The valve stem 19 has screw threaded engagement with a nut 20 that in turn has a screw threaded connection with the valve block 14. A stuffing box or packing retaining member 21 is provided to prevent leakage of fluid along the valve stem 19 and the usual hand wheel 22 is provided for the stem 19, to effect longitudinal movement of the valve 17.

The valve block 14 is preferably cast of brass or similar material and has a drain 100 23 communicating with the chamber in said block.

In Fig. 1 the parts are shown in their normal positions, that is with the main valve 17 closed and the auxiliary valve 10 in its forward or open position. When the main valve 17 is withdrawn slightly, to determine steam or water conditions within the boiler, the valve 10, under the boiler pressure, moves rearwardly somewhat but 105 110

not for such distance as to permit the seating surface 13 thereof to engage the forward end of the valve block. If the valve 17 be then closed the valve 10 will of course 5 be moved forward again against the pressure of the boiler.

When it is desired to grind the valve 17, the hand wheel 22 is rotated a sufficient distance to withdraw the valve 17 until the 10 valve 10 seats against the forward end of the block 14 and seals the forward end of the opening 15. The nut 20 may then be removed from the block 14, carrying with it the valve stem 19 and the valve 17. The 15 valve 17 may thereafter be removed from the stem 19 and reground or a new valve substituted. It will, of course, be apparent that the valve 17 may be rigidly secured to the stem 19, but I prefer to make it separable in order to avoid discarding the entire 20 valve stem when the valve becomes too worn for further grinding, or for convenience in quickly inserting previously ground valves in a valve stem, or for more conveniently 25 manipulating the valve while grinding the same, and further to permit it to more readily seat when closed.

When the parts are reassembled and the 30 valve 17 is moved to its seat, as above described, it of course engages the rear end

of the stem 16 and unseats the auxiliary valve 10, as shown in Fig. 1.

Various changes in detail and general arrangement may be readily made without departing from the spirit and scope as defined in the accompanying claim. 35

I claim as my invention:

Valve structure comprising an auxiliary valve chamber adapted to communicate at its forward end with a source of pressure, 40 a main valve block disposed to the rear of said chamber and whose forward end extends into said chamber, a valve movable longitudinally of said chamber and having radially extending projections that engage 45 the wall of the chamber, a main valve in said valve block, and a spacing member between said valves whereby when the main valve is moved forwardly the auxiliary valve will be moved forwardly, the said 50 radial projections serving as the sole bearing members for said auxiliary valve and providing spaces for the passage of fluid, and the rear end of said auxiliary valve and the forward end of said main valve 55 block having substantially flat co-operating surfaces.

In testimony whereof I, the said GEORGE B. CLARK, have hereunto set my hand.

GEORGE B. CLARK.
